UNITED STATES PATENT OFFICE.

JAMES C. ANDERSON, OF PITTSBURG, PENNSYLVANIA.

IMPROVEMENT IN MACHINES AND PROCESSES FOR DISINTEGRATING CLAY, &c.

Specification forming part of Letters Patent No. 222,225, dated December 2, 1879; application filed April 11, 1879.

To all whom it may concern:

Be it known that I, JAMES C. ANDERSON, of the city of Pittsburg, Allegheny county, and State of Pennsylvania, have invented a new and useful Machine and Process for Disintegrating Clay and Earth Alluvium, and disincorporating and separating the metals therefrom, which process is fully set forth in the following specification.

The invention relates to the disincorporation and separation of the clay and earth of the alluvium from the metallic deposits. Heretofore the clays and earth of such alluvium have been flumed or washed from the ores and metals, which method is objectionable on account of the great difficulty experienced in obtaining an adequate supply of water in many parts of the country abounding in rich gold and silver bearing alluvium deposits, particularly where periodical dry seasons of long duration prevail, and it is also objectionable by reason of the great cost of labor incident to the washing of the alluvium.

The first part of my invention consists in thoroughly drying the alluvium as it is dug from the bed, and then subjecting the mass when dry to rapid concussion and attrition within a suitable rotating cylindrical shell provided with a system of mechanism and screens, which mechanism was patented to me April 22, 1879, No. 214,481, and by which the clay and earth of the alluvium are disintegrated and separated, atom from atom, into a fine powder without crushing or grinding the pebble-like deposits of gold and silver bearing ores and carbonates, which ores and carbonates, together with the coarser particles of gold and silver, are disincorporated intact in the operation, and the powdered clay and earth of the alluvium are made to pass through the screens to a hopper beneath the shell into the hopper I of the mechanism, which I will now proceed to describe, for carrying out the second part of my process and invention, reference being had to the accompanying drawings, in which—

Figure 1 shows a perspective view of the mechanism. Fig. 2 shows a longitudinal vertical central view; and Fig. 3 shows a cross-sectional view of the same.

A cylindrical shell, A, is formed of suitable material and mounted on trunnions C, which

trunnions have their bearings upon the framework D. Suitable openings are made through the center of the trunnions C to admit and allow the shaft E to pass longitudinally through the center of the shell, which shaft is secured rigidly to the frame-work F. A system of arms, H, are keyed to this shaft in a vertical position, extending downwardly in close proximity to the periphery of the shell. To the lower end of each of these are secured plates h, which plates are placed in position with their length across the shell, and are made to converge slightly toward the discharging end of the same in the direction of the arrow-point. An opening, a, is formed in one of the trunnion-heads of the main shell, the sides of which opening are surrounded with a flange extending inwardly in such manner as to allow the alluvium to be fed into the shell by means of the hopper I while the shell is in motion, and to prevent the undue escape of the alluvium, and for that reason the lead side of the opening and flange are inclined corresponding to the incline of the hopper, and for the same reason the flange is made much wider at this edge, as shown by the dotted lines in Fig. 2 of the drawings. A like opening, a', is formed in the other trunnion-head of the shell, which opening is also surrounded by a flange extending inwardly within the shell, through which opening the clay and earth of the alluvium are discharged from the shell.

In the operation the fine disintegrated alluvium-powder passes from the first part of the process into the hopper I, and, the shell being rotated in the direction of the arrow-point by means of the gear-wheel G, the powdered alluvium passes within the opening of the shell by its own gravity. A suitable quantity of quicksilver is placed within the shell for combining and amalgamating with the fine particles of gold and silver of the powdered alluvium. By the rotation of the shell the quicksilver and alluvium are carried well up the sides of the shell, which imparts to them a rapid rolling motion, and brings the alluvium in repeated contact with the quicksilver, which seizes upon and amalgamates with the fine particles of gold and silver contained within the powdered alluvium. The clay is gradually borne from the charging side of the shell in the direction

of the arrow-point to the discharging opening *a* by being driven against the converging plates *h*. These plates are made adjustable for speeding the alluvium through the shell a suitable time to allow the gold and silver particles to be absorbed by the quicksilver, after which the clay and earth separated from the metals are discharged through the opening *a'*. This opening is made a suitable height above the periphery of the shell to prevent the escape of the quicksilver through the opening.

Having thus described my invention, what I claim is—

1. The process herein described for separating the clay and earth of the alluvium from the metals and metallic ores, by first drying

the alluvium, then disintegrating the clay and earth by attrition within a suitable cylindrical shell into a fine powder, and screening the powdered clay and earth from the pebbled ores and metals, substantially as set forth.

2. In combination with the outer shell, *A*, provided with the flanged openings *a* and *a'*, and hopper *I*, the stationary central shaft, *E*, provided with the arms *H* and converging plates *h*, substantially in the manner and for the purpose set forth.

J. C. ANDERSON.
